UNITED STATES PATENT OFFICE

ALBERT DAY, OF CHAPEL ALLERTON, LEEDS, AND WILLIAM HENRY NAYLOR, OF ADEL,
LEEDS, ENGLAND

MACHINE FOR MAKING AND FILLING PACKETS

Application filed April 12, 1930, Serial No. 443,749, and in Great Britain May 1, 1929.

This invention relates to machines for making packets of paper or other wrapping material and filling them with tea, tobacco, seeds or similar substances such as are usually sold in packets, the said machines being of the kind described in the specification of British Patent No. 198,405 in which the wrapping material is formed into a tube on a funnel shaped or other "former" the bottom of 10 the tube being then closed in and a weighed or measured charge of the substance to be packed dropped into the former, after which the filled bag thus produced is transferred to a slotted mould and the top thereof closed in 15 to make a packet. An object of the invention is to facilitate the formation of the tube of paper or the like (hereinafter briefly termed paper) from a travelling strip or a number of sheets of paper fed in a horizontal 20 direction, thus avoiding creasing or tearing of the paper which is liable to occur when it is passed over vertical guides. Another object is to locate the seam or joining of the paper tube in such a position that in the formation 25 of the bag bottom by known folding mechanism the seam side of the tube is first tucked in, thus reducing the liability of the tube to open at the seam in subsequent stages of the process. Another object is to enable 30 the various operations to be rapidly performed while preventing leakage of the substance packed (hereinafter briefly termed tea) and providing for proper settling or consolidation of the tea in the finished 35 packets. Another object is to effect an immediate stoppage of the supply of paper to the machine if the supply of tea fails.

According to the invention a series of 40 formers, each having its upper end enlarged or tapered to receive the charge of tea when the individual former is either in an inclined or vertical position, and each surmounted by a hopper or container to receive the charge 45 of tea and to transfer it to the adjacent former, is caused to revolve intermittently about a central vertical shaft, each former being caused to tilt into a horizontal or inclined position to receive its tube of paper with the 50 seam on its upper surface, and returned to a vertical position, when the seam will be on 55

the side of the former remote from the central shaft. Each former is separated from its superimposed hopper by a flap or valve in the hopper, or a tailpiece on the former can seal the outlet of the hopper so long as the 55 former is in its tilted or outwardly extended position. The formers are associated with a number of rotating or horizontally oscillating slotted moulds which are consecutively brought under the formers to receive the 60 filled bags from them. An electrical or mechanical device which may comprise a feeler adapted to rest on the tea in a filled hopper is so arranged that if the supply of tea fails it stops the feed of paper before a wrapper or 65 sheet of paper is supplied to the former with which the said hopper is associated, or preferably the paper feed stop motion is operated either electrically or mechanically from the 70 weighing or measuring machine.

In order that the said invention may be clearly understood and readily carried into effect, the same will now be described more fully with reference to the accompanying drawing illustrating an embodiment of the 75 invention wherein:

Figure 1 is a side elevation, with the upper parts in central vertical section, of such parts of the machine as are necessary for the explanation of the present invention.

Figure 2 is a plan of the said machine with the parts at the left hand side represented in horizontal section taken on the line 2-2 in Figure 1.

Figure 3 is a sectional plan taken substantially on the line 3 in Figure 1 and illustrating an example of gearing by which the moulds and formers can be operated.

Figure 4 represents one of the formers and one of the hoppers in association with means for preventing a feeding of a sheet of paper in the event of failure of the supply of tea to the machine.

Figure 5 is a detail showing in elevation parts of the mechanism provided for folding the bottom of a tube to make a bag.

Figure 6 is a detail showing in plan other parts of the folding mechanism.

Figure 7 is a detail of mechanism suitable for wrapping the sheet of paper around the 100

lower part of the former to make a paper tube. Figure 8 is an elevation of the cam which produces the oscillation of the formers.

Figure 9 is a detail illustrating a modified arrangement of the hopper and former.

Figure 10 is an elevation of a hopper with the cam seen in section in Figure 4.

Figure 11 is a diagrammatic plan illustrating a segment plate for supporting the bag bottom.

Figure 12 represents in elevation an example of mechanism suitable for feeding paper to the packet making machine.

Figure 13 is a detail of an alternative arrangement of detector mechanism.

On the machine frame 11 is a hollow pillar 12 (Figure 1) on the upper part of which is fixed a cam 13 (Figures 1 and 8). Through this pillar passes a vertical rotary shaft 15 on the upper end of which is secured a disc 16 carrying six or other number of hoppers 17 each of which in turn is brought by the revolution of the shaft and disc under a chute 18 (Figure 9) which constitutes the outlet of a machine of any known or suitable kind for intermittently delivering weighed or measured charges of tea, whereby each hopper is filled in its turn. The open tops of these hoppers, as seen in Figure 2, are of segmental shape to constitute practically an annular hopper divided by radial partitions into six compartments, that is, one to each former. This arrangement gives the maximum open area and thus allows the maximum time for the charge to be placed in each hopper or compartment, so that the machine can be worked at a high speed. Alternatively the hoppers may have rectangular or oval upper openings, the lower opening or outlet being square, round or of other suitable shape according to the cross-sectional shape of the former. Brackets 20 depend from the disc 16, and in bearings 21 at the foot of each bracket is pivotally mounted on trunnions 45 or gudgeon pins 22, an open-topped former 23 underneath each hopper 17. The lower part of the former consists of a tube 24 of square or other suitable cross-section, on which the paper to constitute the wrapper is placed as hereinafter described. From the inner side of the enlarged upper part of each former projects an arm 25 terminating in bearings 26 in which is mounted a roller or runner 27 adapted to travel in the groove 28 of the large cam 13. Each former in its revolution is thereby caused to assume an inclined position as seen at the right hand side of Figure 1 (or if desired a horizontal position) to receive the said paper, and returned to the vertical position to receive the charge of tea from the hopper, which can however, begin to enter the former before the vertical position is reached. On the outer side of each former is pivoted a flap 30, which is also connected by a spring 31 with the upper part of

the former, this spring tending to cause the flap to lie against the outer side of the lower part 24 of the former, in order that the flap may hold in position the "seam" or overlapping part of the paper. From the outer side 70 of the flap projects an arm 32 carrying on its free end a runner 33 adapted to engage a cam plate 39 carried on a beam 35 pivoted on a standard 36 on the machine frame which beam may be rocked by a rod 37 driven from any convenient moving part of the machine. The flap 30 is lifted away from the former by the operation of the cam plate 39 and is kept in a raised position until the seam fold of the paper tube is made. The cam plate 39 is 80 then lowered, allowing the flap 30 to press and hold firmly the seam of the tube until the former has intermittently revolved to the position shown on the left hand side of Figure 1. When the former reaches this position 85 a fixed cam plate 34 (which for the sake of clearness in the drawings, is only indicated in section) engages with the runner 33 thus easing the flap away from the former so as to allow the filled bag to be stripped off the former. In all other positions of the formers the flaps are held closed by the action of the spring 31.

The outlet of each hopper 17 is closed by a pivoted flap or valve 40 which has a tail-piece 41 carrying a runner 42; the weight of the tailpiece may be sufficient to keep the valve closed when required, or springs 43 may connect crossbars 44 (see Figure 2) on the tailpiece with a stud or studs 45 on the 100 boss or bearing 21 of the bracket 20. In order to open the valve 40 positively to allow the charge of tea to fall into the former, the runner 42 is caused to encounter and ride up on a rail or cam path 46 at the left hand 105 side of the machine, which for the sake of clearness is only indicated in section in the drawings. The cam path 46 as well as the cam path 34 may be replaced by positively moving actuating mechanism if desired. Instead of the valve 40 there may be a curved flap or tailpiece 47 (Figure 9) on the former working in the lower part 48 of the hopper 17, so that when the former 23 is in the position shown, the outlet of the hopper is closed, but when the former is returning to its vertical position the tea is admitted thereto, and thus only the cam 13 is needed to effect automatically the oscillation of the formers 23 and the control of the admission of the charge to each former as the shaft 15 revolves. A former with the bag thereon can receive the full charge from the hopper 17 either when the former is in a vertical or inclined position, owing to its enlarged upper end or mouthpiece as before mentioned; where a flap or valve is employed as aforesaid, the charge can be delivered to the hopper prior to the making of the bag on the former, and this in turn permits the paper 115 120 125 130

feed to be stopped if necessary before a wrapper reaches the former which is then in position to receive a wrapper.

In the case of the former with a tailpiece (Figure 9) the tea may also be delivered to the hopper 17 prior to the making of the bag. This also allows the paper feed to be stopped when required, as hereinafter described. The former must however, remain in the inclined position until the end fold of the bag is completed, after which the former may resume its vertical position. Also the former with the tailpiece would require to be raised to its inclined position after the filled bag has been stripped from the former and before the tea is delivered into the hopper 17.

The charge of tea from the weighing machine is delivered to the hopper 17 at the position A (Figure 11) after which the hopper moves to position B, at which a feeler 105 (Figure 4) engages a cam plate 107 on the hopper, and if the weighing machine has not delivered its charge, the feeler 105 can descend into the hopper and cause the stoppage of the paper feed as hereinafter described. If the charge is in the hopper, the paper tube is supplied to the former at position C, the folding in of the bottom of the tube to make a bag takes place at position D, the transfer of the charge to the former at position E, and the transfer of the filled bag to the mould at position F.

The feeding of the paper 50 and the cutting thereof into sheets of a suitable size, are effected by any suitable mechanism (for example, the mechanism represented in Figure 12), which lays each sheet across the underside of the lower part 24 of the former when in the position represented at the right hand side of Figure 1, pivoted arms or bell-crank levers 51 (Figure 7) being then caused to close on the paper and wrap it over the part 24 with its "seam" or overlapping edges uppermost, after which the flap 30 closes on the seam and the former proceeds on its intermittent revolution around the shaft 15. A portion of the tube of paper which projects below the open lower end of the former is then tucked in or folded from the side on which the seam is located across the said lower end by the first folder 52 (Figure 5). The second folder 53 and the third folder 54 (Figure 6) then fold in parts of the pendent paper tube at each side of the former across the first fold, after which the fourth folder 55 (Figure 5) presses inwardly the remaining triangular part or "ear" of the paper to complete the bag bottom. Rotation being resumed, the bag still on the former is then carried round in the direction of the arrow, Figure 11, with its folded bottom resting on a flat segment plate 79 to preserve its folded condition while receiving and travelling with its charge of tea.

The segment plate, which has lugs by which it is fixed in position, is for the sake of clearness omitted from the drawing Figures 1 and 2. The fall of the tea into the hollow former 24 may take place at any time 70 between the turning in by the first folder 52 (Figure 5) of the first fold of the bag, thus covering the bottom of the outlet of the former, and the stripping of the filled bag from the former, but in this example 75 the fall of the tea into the former is arranged to take place at the position marked E in Figure 11, at which the former comes to rest momentarily. In some instances it may be preferable to substitute for the first 80 folder 52 a thin flat plate which moves to and away from the under side of the former. This allows the side folders 53 and 54 (Figure 6) to make their folds over the plate; the plate remaining underneath the bottom 85 of the former acts as a false bottom or cover plate to prevent the escape of the tea when it is deposited into the bag in this position.

When the former 23 has arrived at the position shown in the left hand side of Figure 1 a stripper 56 advances to engage the bag and descends to strip it off the former, a finger or folder 49 on the stripper (Figures 1 and 11) remaining in contact with the bag bottom while the charge which is resting on the bag bottom and contained within the former, drops out of the former into the bag. 90

The filled bag is lowered into one of a series of moulds 58 carried on a rotary mould table 59; the outer side of the mould is 100 slotted as seen in Figures 2 and 11 to allow the finger 49 to pass down to the bottom of the mould through the wall of the mould, while this finger 49 controls the ear at the bag bottom during the time the folded bag 105 is being taken from the former to the mould.

At the bottom of the mould the bag is supported by an annular plate 114 (Figure 1) which prevents the flaps or ears of the bag bottom from opening and the table 59 is 110 rotated one step to carry away the filled bag and bring an empty mould under the former. The top of the filled bag is closed at another position of the rotary table by any known or suitable means. The angular 115 speed of rotation of the mould table 59 is less than that of the disc 16, so that ten moulds can be filled in turn by six formers. When by the next step of rotation of the mould table the filled packet is removed from 120 the filling station F, it can be taken from the mould by hand or ejected therefrom by suitable mechanism, which does not form any part of the present invention, and labelled by hand; or it can be transferred 125 to a trough in which the packets successively received from the machine are caused to travel in close contact with each other, so as to prevent opening of their folded ends, although there is usually very little tend- 130

ency of the packets to burst open. They can be taken from the said trough to another machine in which their ends are secured in position by adhesive labels, for example by a machine such as that described in the specification of British Patent No. 200,878.

The gearing for effecting the intermittent rotation of the shaft 15 and table 59 and the movements of the wrapping arms 51 and stripper 56 may be of any suitable kind, but an example of one arrangement is represented in Figures 1 and 3. There are three rotary shafts 61, 62, 63, the two latter being cam shafts, and two fixed shafts 64 and 65. 15 A spindle 66 suitably supported in the framework of the machine carries the mould table 59 at its upper end and a star wheel 67 at its lower end. A bevel pinion 68 on the shaft 61 drives a bevel pinion 69 loose on a vertical stud 70 depending from a convenient portion of the framework of the machine, and on the boss of this pinion 69 is a small stud 71 carrying a bowl or runner 72 adapted to enter consecutively the recesses 73 in the star wheel 67 and to impart an intermittent rotary movement to this wheel 67 and thus to the mould table 59.

Another star wheel 74 is secured to the lower part of the vertical shaft 15. A bevel pinion 75 on the horizontal shaft 62 drives a bevel pinion 76 on a vertical stud 77, and on the boss 78 of the pinion 76 is a crank 80 carrying a bowl or runner 81 adapted to work in the recesses 82 in the star wheel 74 and thereby to cause intermittent rotation of the shaft 15 with the hoppers and formers.

On the shaft 64 is freely mounted a two-armed lever, one arm 83 of which carries a runner 84 in contact with a cam 85 on the shaft 62, while the other arm 86 is connected by a link 87 with the stripper 56. The lower end of the stripper 56 is steadied by an arm 88 of a two-armed lever mounted on the shaft 64. The other arm 93 carries a runner 94 in contact with a cam 90. The raising and lowering of the stripper 56 is controlled by the lever 88 and the moving of the stripper to and away from the former is controlled by the lever 86 and link 87 together with cams 85 and 90 respectively. A lever 95, free to turn on the shaft 64 carries a runner 96 in contact with cam 91. The said arm 95 is connected by a rod 97 of adjustable length with a lever 98 pivoted to the machine frame at 101 so that the said lever 98 can be rocked by the movements of the cam 91. On the free end of this lever 98 are pivoted at 89 (see Figure 7) the two arms 51 aforesaid for wrapping the sheet of paper around the lower part 24 of the former. These pivoted arms are operated through rods 102 of adjustable length by a lever 103 pivoted on the shaft 65, this lever

carrying a runner 104 in contact with the cam 92.

The mechanism for operating the folders 52, 53, 54 and 55 may be similar to that described in the specification of the prior British Patent No. 198,405.

The mechanism for feeding the paper to the machine which mechanism does not form a part of this invention, may comprise a ratchet wheel and pawl or pawls, the action of the pawl being controlled by a magnet. This magnet may be part of an electric circuit which is closed to stop the paper feed at station B (Figure 11) when the feeler 105 is in the position seen in Figure 4, that is, 75 its lowest position in the hopper 17, due to absence of the charge of tea which should have been admitted at station A to the hopper, the delivery from the weighing machine having failed. The feeler 105 is pivoted at 80 112 to an arm 106 and engages a cam plate 107 (Figure 10) which is shown in section in Figure 4. Such a cam plate is secured to each hopper 17 and in each revolution of the disc 16 passes under the feeler 105, a recess 85 110 allowing the feeler to drop unless supported by the charge. At the end of the feeler remote from that which enters the hopper is an electrical contact piece 108. When the feeler 105 rocks on its pivot into 90 the position shown due to there being no tea in the hopper 17, the opposite end of the feeler rises and the piece 108 makes electrical contact with the fixed contact piece 109, mounted on a support 106 in the machine 100 frame, to close the circuit. As the hopper proceeds on its intermittent revolution the cam plate rocks the feeler to lift it clear of the top of the hopper.

Alternatively, the feeler 105 could be operated by mechanical means as illustrated and described in patent specification 198,405.

When operated either mechanically or electrically, a charge of tea within the hopper 17 holds the feeler in the middle position, 110 thus allowing the pawls of the paper feeding mechanism to feed a length of paper.

It is preferable however, that the electrical circuit should be closed by the weighing machine so that in the event of a failure of the supply of a charge of tea, a suspension of the paper feed could take place without the use of the feeler 105.

Referring to Figure 12, the frame 121 carries bearings 122 in which a reel 123 of paper can revolve freely. The web of paper 50 coming from the reel is led between friction rollers 124 and 125, the latter roller being intermittently rotated by mechanism herein-after described. Thence the paper passes between guide rollers 126, 127, and over a ledge 128, in contact with which a guillotine knife 129 is vertically reciprocated by any suitable means to cut the travelling paper into sheets each adapted to constitute the wrapper of 130

one packet. In the lower part of the frame 121 is mounted a shaft 130 on which are secured a crank 131 and a cam 132. This shaft 130 may be driven from any convenient source of power; for example it may be driven by a chain drive from the shaft 63 in the main machine, Figure 1, and in that case the sprocket pulley on the shaft 130 should be twice the size of the sprocket pulley on the shaft 63, so that the shaft 130 will rotate at half the speed of the shaft 63. The crank 131 is operatively connected by a link 133 with one arm of a bell crank lever 134, loose on the shaft 135 of the pulley 125, the other arm of which lever carries one or more pivoted pawls 136, two of such pawls being shown. The pawls are adapted to engage a ratchet wheel 137 fastened on the shaft 135, and thereby to impart an intermittent motion to the paper feeding pulley 125. A three armed lever 140 pivoted to the frame 121 at 141 carries at its lower extremity a bowl or runner 142 normally in contact with the cam 132, which cam thus rocks the lever 140 and by means of a link 143 attached thereto causes a semi-circular arm 144 to lift the pawls 136 clear of the teeth of the ratchet wheel, and as the swell or highest part of the cam's periphery passes out of contact with the runner 142 the lever 140 returns and causes the arm 144 to be lowered, enabling the pawls 136 to feed the paper. A magnet 145 is electrically connected with the weighing machine (not shown) and acts on a pivoted lever 146 comprising a catch 147 adapted to engage the third arm of the lever 140, when a spring 148 anchored to the frame 121 tends to hold the catch 147 in engagement. Each time the proper action of the weighing machine in delivering a charge takes place, the circuit in the weighing machine is closed and the current passing through the magnet 145 causes it to overcome the effort of the spring 148 and draw the catch 147 clear of the lever 140, allowing the runner 142 to follow the cam 132 and the feeding of a sheet of paper to be effected; but if the charge of tea is not delivered, the spring 148 prevents the release of the catch 147, so that the paper feed is stopped. When the electrical control is effected by the arm 105 (Figure 4) the relative positions of the magnet 145 and spring 148 are reversed, as shown in Figure 13, and the circuit completed through 106, 108 due to the lack of material in the hopper 48 causes the catch 147 to engage the lever 140 and hold the latter in its inoperative position until the arm 105 is lifted by the cam path 107.

60. What we claim and desire to secure by Letters Patent of the United States is:—

1. In a machine for making and filling packets, a member intermittently rotatable about a vertical axis, a series of charge receptacles surrounding and carried by said rotary

member, a series of hollow formers each pivotally suspended from said rotary member, each of said formers being adapted to receive a charge from the associated receptacle, means to tilt each former consecutively, means to supply a sheet of wrapping material to the under side of the former when so tilted, means to fold said sheet into a tubular shape around the former with the overlapping edges of said sheet located on the side of the former which is turned away from the axis of rotation of said member, means to hold said sheet on the former during the subsequent part of its revolution, means to turn in the bottom of said sheet to form a bag, and means to strip said bag with the charge therein from the former.

2. In a machine for making and filling packets, a member intermittently rotatable about a vertical axis, a series of charge receptacles surrounding and carried by said rotary member, a series of hollow formers each suspended from said rotary member under a receptacle, each of said formers being adapted to receive a charge from the associated receptacle, a pivoted flap valve to control the passage of said charge from said receptacle to said former, said valve having an external arm, a cam to engage said arm at a predetermined point in the revolution of said receptacle to open said valve, means to apply a sheet of wrapping material to said former, means to form said sheet into a bag, and means to strip said bag with the charge therein from the former.

3. In a machine for making and filling packets, a member intermittently rotatable about a vertical axis, a series of charge receptacles surrounding and carried by said rotary member and having open outlets, a series of hollow formers each pivotally suspended from said rotary member under a receptacle, each of said formers being adapted to receive a charge from the associated receptacle, means to tilt each former consecutively, a tail-piece on said former to close the outlet of said associated receptacle when said former is so tilted, means to apply a sheet of wrapping material to said former while the latter is in its tilted position, means to form said sheet into a bag, and means to strip said bag with the charge therein from the former.

4. In a machine for making and filling packets, a member intermittently rotatable about a vertical axis, a series of charge receptacles surrounding and carried by said rotary member, a series of hollow formers each suspended from said rotary member under a corresponding one of said receptacles to receive a charge therefrom, means to feed sheets of wrapping material to said formers, said feeding means being rendered inoperative by the closure of an electric circuit, a pivoted detector adapted to close said circuit, said detector entering each receptacle in succession as

the receptacles revolve, and being supported in an inoperative position by the charge therein, but becoming operative to stop the feed of paper on the absence of a charge in said receptacle.

5. In a machine for making and filling packets, a member intermittently rotatable about a vertical axis, a series of charge receptacles surrounding and carried by said rotary member, a series of hollow formers each pivotally suspended from said rotary member, each of said formers being adapted to receive a charge from the associated receptacle, a stationary grooved cam, means on each former to engage the groove in said cam, whereby said former is tilted at a predetermined point in its rotation, and then returned to a vertical position, means to supply a sheet of wrapping material to the under side of the former when so tilted, means to fold said sheet into a tubular shape around the former with the overlapping edges of said sheet located on the side of the former which is turned away from the axis of rotation of said member, means to hold said sheet on the former during the subsequent part of its revolution, means to turn in the bottom of said sheet to form a bag, and means to strip said bag with the charge therein from the former.
- 20 6. In a machine for making and filling packets, a member intermittently rotatable about a vertical axis, a series of charge receptacles surrounding and carried by said rotary member, a series of hollow formers each pivotally suspended from said rotary member, each of said formers being adapted to receive a charge from the associated receptacle, means to tilt each former consecutively, means to supply a sheet of wrapping material to the under side of the former when so tilted, means to fold said sheet into a tubular shape around the former with the overlapping edges of said sheet located on the side of the former which is turned away from the axis of rotation of said member, a flap pivoted on each former and having a projecting arm, a spring tending to hold said flap against the lower part of the former, a cam adapted to actuate said arm to lift said flap clear of said lower part at a predetermined point in the revolution of the former to permit of said folding, said cam then permitting said flap to be returned by the spring and thereby to hold said sheet while the revolution of the former continues, means to turn in the bottom of said sheet to form a bag, and means to strip said bag with the charge therein from the former.
- 45 7. In a machine for making and filling packets, a vertical shaft, gearing to impart intermittent angular movement to said shaft, a stationary cam surrounding a portion of the length of said shaft, a disc secured on said shaft carrying a plurality of charge receptacles, a plurality of hollow formers piv-

otally suspended from said disc, one under and in alignment with each of said receptacles, each of said formers comprising a tubular chute and each having above said chute a projection in operative engagement with said cam to tilt the former outwardly and upwardly at a predetermined point in its revolution around the shaft and then to restore said former to a vertical position, a flap pivoted on the upper part of the former and normally held by a spring in contact with the outer side of the chute of the former, means to lift said flap clear of said chute simultaneously with the tilting of the former, means to apply a sheet of wrapping material to the underside of said chute, means to wrap said sheet around said chute to form said sheet into a tube with the edges of said sheet overlapping each other at the upper side of said chute, whereafter the flap is returned by the spring to hold said edges, means operative at a further step of angular movement of the former around the vertical shaft to close in the bottom of the tube of wrapping material to form a bag, a segmental plate to support the bag bottom during its further angular movement, a mold to receive the bag and a vertically moving stripper to transfer the bag from the exterior of the former together with the charge from the interior of the former to said mold.

ALBERT DAY.

WILLIAM HENRY NAYLOR.
